UNITED STATES PATENT OFFICE.

ALBERT H. HONEY, OF LOS ANGELES, CALIFORNIA.

MAKE-UP FRAME FOR X-RAY PHOTOGRAPHY.

Application filed October 23, 1924. Serial No. 745,300.

This invention has to do with the production of assembled, regional or sectional X-ray photographs or the like; and it may be stated as one of the general objects of the 5 invention to provide means whereby a final assembled photograph reproduction may be produced, embodying in any suitable or proper arrangement all or any desired portions of the sectional or regional X-ray 10 photographs originally taken, and all in such integral form and with the photographs so relatively arranged, that the final product may be easily handled and readily viewed and interpreted.

15 In describing my invention I will describe it for instance as applied to the X-ray photography of the teeth; although it will be understood that the invention is not necessarily limited to such application. It has 20 been the custom in the past to take an original series or several series of X-ray exposures from various aspects; so that several final photographs will make up a complete set or sets of pictures of the teeth in the 25 various desired aspects. These photographs, usually in the form of films, or reproductions from them, have commonly been loosely mounted on a sheet of translucent material; but in such usage there is always a liability 30 of such photographs becoming intact and lost or of their being placed out of proper relative arrangement. Furthermore, in such photographs there are usually some parts of each exposure that are either substantial 35 duplicates of parts in another exposure, or there are some parts that were not in proper focus in one exposure and that are reproduced in other exposures in proper focus. The common method of mounting has been 40 such that only a full-sized photograph can be readily attached to the translucent sheet; and this precludes any practicability of cutting down any of the photographs to cut out the unsatisfactory or duplicated portions.

45 By my invention it is not only made possible to do away with the separate loosely mounted photograph but it is also made possible at the same time to have the individual photographs cut down in any desired manner to obliterate any objectionable part in the 50 final photograph reproduction.

The manner in which these things are done will be best understood from the following specification and the accompanying drawings in which I illustrate my preferred form

of make-up frame, which preferred form is typical of the invention. In these drawings Fig. 1 is a face view of the make-up frame with various originals therein and also cards carrying identification matter; Fig. 2 is an enlarged cross-section of the make-up frame taken on line 2-2 of Fig. 1; Fig. 3 is a face view of the final assembled photographic reproduction; Fig. 4 is a detailed perspective of one of the carriers used in the 60 make-up frame; Fig. 5 is a horizontal section of the carrier; and Fig. 6 is a vertical section thereof.

In the drawings I show the make-up frame as comprising a suitable plate 10 which may 70 conveniently be of any material, or metal, opaque to ordinary light rays. For instance, an aluminum plate is satisfactory on account of its lightness. For the particular application of the invention to production of assembled X-rayed photographs of teeth, I provide the plate with two rather long apertures 11 and 12 and at the top and bottom of these apertures I arrange guides or slide-ways that are easily constructed by an under-strip 13 and an outer wider strip 14 overhanging the edges of the under strip to form slide-ways as illustrated. These slide-ways are open at both ends so that the carriers 15 may be easily inserted into such positions as are shown in Fig. 1. Each carrier has apertures through it for the exposure of the photograph 16 carried therein. Preferably I make these carriers from a single sheet of thin and rather springy metal, bent 80 double at the edge shown at 17 in Fig. 4, so that the carrier has two leaves, so to speak, illustrated at 18 and 19 in Fig. 4. Each leaf has an aperture 20, the two apertures registering; and one of the leaves may have an 85 edge, as shown at 21 that overhangs the adjacent edge of the other leaf so as to afford an edge that may be engaged by the finger for the purpose of separating the two leaves. The carrier as thus formed may preferably 90 be made so that the two leaves have a tendency to spring together. They are shown somewhat sprung apart in Fig. 4 for purposes of illustration. The springing together of the two leaves tends to hold the 95 photograph tightly between them.

All of the carriers are made of uniform height so that their upper and lower edges may be fitted in the slide-ways at opposite edges of a plate aperture 11 and 12. How- 100 105 110 115

ever, the carriers may be, and usually will be, made of different widths so as to accommodate photographs of different width dimensions. The height dimension of each carrier 5 is sufficient to accommodate the maximum height of photograph used; but the width dimensions of the several carriers will be determined by the desired width dimension of the respective carrier openings 20, so as to 10 use only a narrow margin between the vertical edges of the opening and the vertical edges of the carrier. In using my device the user will be provided with a fair number of carriers having openings of different dimensions both as to height and width, so that 15 by placing a photograph in any selected carrier all undesired parts of that photograph may be blocked out and only the desired parts show through the carrier openings.

20 The proper carriers having been selected for the various photographs, these carriers with their photographs within them are slid into the slide-ways closely adjacent each other so that their edges meet tightly enough 25 to prevent transmission of light between adjacent carriers. If all of the opening 11 or 12 is not covered by the carriers and their photographs, an opaque blank or blanks 25 may be inserted as shown in Fig. 1.

30 Above the uppermost slideway 14 there may be an opening or openings 30 with slide ways 31 above them for the insertion of transparencies 32 carrying suitable identification data. The number of these openings and the proper selection of data to be carried by the transparencies is to be determined by the user. It will of course, be understood that the number of openings 11, 12, and 30 may be varied; and likewise the 35 size of the device and its capacity as the size and number of photographs may be varied. The device shown in the drawings has been found convenient as to arrangement for X-ray photographs of teeth.

40 Having taken the original X-ray exposures as desired, and having developed them, either these original negatives or positives made from these original negatives are placed in the make-up frame as before described.

50 It will of course be recognized that by proper selection of the carriers for the several photographs and by proper relative arrangement of the carriers with their photographs, the photographs may be arranged in such a way as to give a comprehensive view of the whole photographed subject matter, without any duplications and without the exposure of parts that have not 55 been properly photographed by reason of being out of focus or for any other reason.

60 The whole assembly having been properly arranged, a photographic print is next made of that whole assembly. While this photographic print may be obtained by any sys-

tem of printing, such as by simple light transmission directly from the composite make-up to a film or photographic plate, it is most highly desirable, for the purposes of greatest possible accuracy of reproduction, that the final photograph be made by the method of projection printing. For this purpose the composite make-up is placed in the plate carrier of a projection printer, (an enlarging or reducing camera) 70 and an evenly illuminated white card is placed behind the composite make-up. Any photographic plate or film may be placed in the other plate carrier of the projection printer, but I prefer to use a heavy celluloid 75 or other film carrying a suitable sensitized emulsion. After proper focusing of the image on this film, at the size of the reproduction desired, the proper exposure is made; and upon developing the film and 80 making a positive I then have a film or other body such as shown at 40 in Fig. 3, which is dark or substantially opaque over the major portion of its surface, with comparatively transparent portions on its surface 85 corresponding in size and relative position to the transparencies that have been put into the composite make-up, and with photographic reproductions of the original transparencies in its transparent portions. 90 These final photographic reproductions may of course, if desired by the user, be either duplicates of the original negatives taken by X-ray or may be positives of those negatives. In addition to the various advantages 95 of my system that have been hereinbefore set out, it will be seen that I produce a final photographic record film or the like that is comparatively opaque over its entire surface except in portions of the actual pictures, 100 which are comparatively transparent. This opaqueness surrounding the transparent or semitransparent pictures aids very clearly in inspection of the pictures themselves as the light of transmission by which the pictures are viewed is confined to the pictures alone.

105 Having described a preferred form of my invention, I claim:

1. A make-up device for holding a plurality of transparencies to be collectively photographed, embodying an opaque plate with an opening therethrough and slide ways on opposite sides of the opening, a plurality of opaque transparency carriers of uniform height dimension adapted to fit into said slideways and collectively cover said opening, said carriers embodying two leaves with registering apertures therethrough and said apertures in the several carriers being of different dimensions so as to expose transparencies of different sizes. 115

120 2. In a device of the character described, a carrier embodying a single sheet of thin spring metal bent upon itself forming two 130

leaves and the leaves tending to spring against each other to hold a transparency or the like between them, the leaves having registering openings, and an edge of one leaf projecting beyond the corresponding edge of the other to facilitate manual engagement for separation of the leaves.

3. A make-up device for holding a plurality of transparencies to be collectively photographed, embodying an opaque plate with an elongated opening therethrough and slideways along opposite longitudinal edges of the opening, a plurality of opaque trans-

parency carriers of uniform height dimension adapted to fit into said slideways, having horizontal dimensions less than the length of the opening, adapted to abut at their edges and collectively adapted to cover the opening, each of said carriers having an aperture completely through it and through which a carried transparency is exposed.

In witness that I claim the foregoing I have hereunto subscribed my name this 5th day of September, 1924.

ALBERT H. HONEY.
